UNITED STATES PATENT OFFICE.

EDWIN FRANCIS CREAGER, OF LANCASTER, PENNSYLVANIA, ASSIGNOR TO
HUBLEY MANUFACTURING COMPANY, OF SAME PLACE.

DESIGN FOR A TOY BANK.

SPECIFICATION forming part of Design No. 34,595, dated May 28, 1901.

Application filed February 26, 1901. Serial No. 49,007. Term of patent 7 years.

To all whom it may concern:

Be it known that I, EDWIN FRANCIS CREAGER, a citizen of the United States, residing at Lancaster, in the county of Lancaster and 5 State of Pennsylvania, have invented a certain original new and useful Design for Toy Banks; and I do hereby declare the following to be a full, clear, and exact description of the invention, such as will enable others skilled 10 in the art to which it appertains to make and use the same.

This invention relates to a design for a toy savings-bank in the form of a statuette of a negro boy in negligée costume.

15 In the accompanying drawings, Figure 1 is a front elevation. Fig. 2 is a side elevation, and Fig. 3 is a rear elevation.

The figure is shown with a hat upon the

head and as clad in shirt, trousers, and shoes. The arms are represented as slightly akimbo, 20 with the hands buried in pockets. Throughout the figure the lines are arranged to convey an impression of the attributes of race and character. At the rear of the neck, but so placed that it does not interfere with the 25 general contour of the figure, a slit is indicated.

What I claim is—

The design for a toy bank substantially as shown and described.

In testimony whereof I affix my signature in presence of two witnesses.

EDWIN FRANCIS CREAGER.
